UNITED STATES PATENT OFFICE.

F. RUSSELL WOODWARD, OF ATTLEBORO, MASSACHUSETTS, ASSIGNOR TO THE WATSON COMPANY, OF ATTLEBORO, MASSACHUSETTS.

DESIGN FOR A HANDLE FOR A SPOON, FORK, OR SIMILAR ARTICLE.

57,197.

Specification for Design.

Patented Mar. 1, 1921.

Application filed July 23, 1920. Serial No. 398,592. Term of patent 14 years.

To all whom it may concern:

Be it known that I, F. RUSSELL Woodward, a citizen of the United States, residing at Attleboro, county of Bristol, and State of Massachusetts, have invented a new, original, and ornamental Design for a Handle for a Spoon, Fork, or Similar Article, which is illustrated in the accompanying drawing, forming part of this application.

Figure 1 is a view of the design in front elevation. Fig. 2 is a fragmentary perspective view on the line A—A of Fig. 1.

I claim:

The ornamental design for a handle for a spoon, fork, or similar article as shown.

F. RUSSELL WOODWARD.
